UNITED STATES PATENT OFFICE.

FRANK W. KELLER, OF KANSAS CITY, MISSOURI

MONOLITHIC-PIPE MOLD.

1,146,263.

Specification of Letters Patent. Patented July 13, 1915.

Application filed February 21, 1913. Serial No. 749,996.

To all whom it may concern:

Be it known that I, FRANK W. KELLER, a citizen of the United States, residing at Kansas City, in the county of Jackson and 5 State of Missouri, have invented certain new and useful Improvements in Monolithic Pipe Molds; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 My invention relates to monolithic pipe molds, and more particularly to an apparatus of that type for making pipe in the trenches wherein sewer, water, or like pipe 20 is usually laid; the principal object of the invention being to provide a sectional mold which may be assembled as the work progresses, and which may be adjusted to form pipe of different diameters.

25 It is also an object of my invention to provide a mold of this type wherein the separate sections may not only be assembled upon each other to form a continuous mold of the desired diameter, but in which each 30 section may be made to taper, to provide for specified enlargements or contractions, and in which the sections may be assembled at an angle to provide for curves or turns.

The apparatus consists, generically, of a 35 plurality of independent, expansible mold sections, which are made to overlap, and are expanded circumferentially to form an integral unit, base blocks upon which the sections are supported and to which said sections are tied to prevent floating when the 40 plastic mass is poured about the mold; and a top shaper for determining the shape of the upper portion of the pipe, the preferred form of structure of such parts being 45 illustrated in the accompanying drawings, wherein:

Figure I is an end view of a mold constructed according to my invention, showing its position in a trench, ready for the 50 pouring of the concrete. Fig. II is a side elevation of the same, parts being broken away for better illustration. Fig. III is a perspective view of the top shaper. Fig. IV is a perspective view of the mold core supporting and anchoring block. Fig. V is a perspective view of the mold core in ex-

panded position. Fig. VI is an end view of two core sections, showing one of the cores locked in open position, and the other section collapsed and supported on the rails of 60 the inclosing section. Fig. VII is a perspective view of the joint between two core sections, parts being broken away to show the expansible ring. Fig. VIII is a perspective view of the expansible ring. Fig. 65 IX is a side view of the core showing the method of tapering a conduit for reductions or enlargements. Fig. X is a plan view of two sections of the core, showing the method of laying a curved conduit. Fig. XI is a 70 perspective view of an attachment for forming manholes, branches, etc. Fig. XII is an end view of a modified form of core.

Referring more in details to the part:—1 designates the mold core sections, which are 75 preferably formed of sheet steel, and of such weight that they may be easily handled by two men, each section being curved so that it may be shaped into a cylinder having overlapped edges 2. Near the edge of 80 each core section are apertures 3 which are adapted for receiving tie wires 4 to hold the piece in cylindrical form when its edges are overlapped, and which are arranged in sets so that the diameter of the core may be 85 varied.

Rigidly secured to the inner face of the core form, opposite the overlapping edges 2, are parallel angle bars 5 which stiffen the metal and provide rails over which other 90 sections may travel when the mold is taken down (as presently described) and which terminate short of the ends of the cores to provide space 6 for receiving adjacent sections at one end and an expansion ring 7 95 at the other, each rail having apertures 5' in its ends for receiving the end of a hook by which the core may be removed. The ring 7 preferably comprises a channel member formed into a circle, the outside diameter of 100 which is slightly less than the inside diameter of the pipe, and the ends of which are spaced apart and provided with blocks 8 for receiving the right and left handed screw 9, whereby the ring is expanded or 105 contracted.

The joints of the core sections are adapted to rest on concrete blocks 10, each of which has a base portion 11, of sufficient width to provide a substantial foundation or support, 110 and a vertical seat portion 12, the upper surface of which is curved to the radius of the

pipe. Embedded in the seat portion of each block is a wire 13, the free ends of which are extended up around the core form and twisted to hold the telescoping sections to the anchor block, the wires being of sufficient length, however, to extend above the curved end rails 14 of a top shaping member 15 about which it is also twisted.

The shaping member comprises curved plates 16 which are secured to the under sides of the end rails 14 and are spaced to leave a longitudinal center opening 17 through which the material may be poured, the plates being provided with strips 18 adjacent each side of the opening 17 whereby the material is stiffened and protected.

Each of the plates 16 has end portions 19 projected beyond the rails 14 to overlap like projections on adjacent shapers. Pivotally mounted on the end rails 14 are standards 20, which are adapted to rest on the core form, and space the top shaper from the form a distance equal to the desired thickness of the pipe, and for folding upwardly out of such space when the material has been poured, in order that the material may set solidly around the core.

In using the forms, a trench, having substantially the outside dimensions of the pipe or conduit, is dug, and the concrete blocks 9 set in position as shown in Figs. I and II. A core form is then positioned on the blocks and opened to the proper diameter and tied by wires 4, which are passed through the proper sets of apertures 3 and twisted to hold the core to the desired diameter.

When a first core section is in place a second section is placed in position and its forward end tied to hold it to the given diameter, the other end being compressed and projected into the end of the first section. An expanding ring 7 is then applied to the untied, contained end of the second section and the screw operated to expand the ring and press the loose shell out against the first section, to hold the parts firmly together and form a relatively integral structure. Succeeding sections are then similarly placed, a workman usually following inside of the core to guide the new sections and clamp the rings in position.

As soon as the new section is placed, the wires 13 are twisted tightly over the joints to hold the core to the anchor blocks and prevent the cores from floating when the concrete is poured, and the top shaping members 15 are set in position with the standards 20 resting on the core forms, and the free ends of the wires twisted over the end rails 14 to complete the mold. Concrete is then poured through opening 17 to fill the cavity formed by the walls of the ditch, the core forms and the top plates, and while the concrete is yet in a fluid state the standards 20 are turned, as shown in dotted

lines (Fig. III), so that the apertures they would otherwise leave may be filled, it being apparent that the concrete blocks 10 will be surrounded on the sides by the fresh concrete and form an integral structure therewith.

When the concrete has set, an attendant enters the core forms, removes the rings 8 and cuts the wires 4 so that the forms will collapse, as shown in Fig. VI, and can be reset by drawing them along the other core sections until they drop from the rails 4 in the front sections, and are supported on the extended portion of said front sections to form extensions of the mold.

In order to make enlargements or reduce the size of the pipe, the core forms may be secured at one end by a wire 4, as shown in Fig. IX, and joined to adjacent sections in the ordinary manner.

Fig. X shows a method of arranging the forms around curves, which has been found to be very practical, and is practised by turning each section a little farther out of the longitudinal axis of the pipe and expanding the ring 7 to conform to the slight variation in diameter.

In using the mold for making concrete sewers or conduits, manholes and branches are necessary, and in order to form them of concrete, or provide a footing for manholes constructed of brick, or concrete, I have provided the form shown in Fig. XI, which comprises a pair of curved plates having body portions 24 adapted to seat over the main cores, and having end portions 25 adapted to overlap to complete a stub, the overlapping portions being provided with apertures 3 and adapted for connection by line wires 4, as in the main core sections. It is apparent that with this construction the plates 23 may be set for any desired diameter, and may be held rigid by placing an expanding ring 7 therein.

If the manhole is to be also constructed of concrete, one of the sections 1 may be placed upright and expanded in the cylindrical piece 24 to form an upright core, it being apparent that the outer part of the mold may be constructed in any suitable manner.

Although I have described the forms as cylindrical in shape I do not wish to be limited to this particular shape, as the elliptical form shown in Fig. XII is very efficient in some cases and is believed to lie within the scope of this invention.

Having thus described my invention, what I claim as new therein, and desire to secure by Letters Patent, is:

1. The combination of a plurality of core members, each having one end located in the end of an adjacent member and having lapped longitudinal edges, means tying the lapped edges at the outer end of each core, and an expansion ring located within the

untied end of the contained core and pressing the same against the tied end of the containing core.

2. The combination of a plurality of core members, each having one end located in the end of an adjacent member and having lapped longitudinal edges, means tying the lapped edges at the outer end of each core, an expansion ring located within the untied end of the contained core and pressing the same against the tied end of the containing

core, base blocks supporting the cores at the telescoping joints, and tie members embedded in the base block and inclosing the jointed portions of the cores.

15 In testimony whereof I affix my signature in presence of two witnesses.

FRANK W. KELLER.
